UNITED STATES PATENT OFFICE.

THOMAS I. RANKIN, OF PHILADELPHIA, PENNSYLVANIA, ASSIGNOR TO THE
ABRAM COX STOVE COMPANY, OF SAME PLACE.

DESIGN FOR A COOKING-STOVE.

SPECIFICATION forming part of Design No. 29,587, dated November 1, 1898.

Application filed September 28, 1898. Serial No. 692,139. Term of patent 34 years.

To all whom it may concern:

Be it known that I, THOMAS I. RANKIN, a citizen of the United States, residing in Philadelphia, Pennsylvania, have invented and produced a certain new and useful Design for a Cooking-Stove, of which the following is a specification.

My design for a cooking-stove is fully illustrated in the accompanying drawing, the figure of which represents the stove in perspective.

The essential feature of the design is a cooking-stove having lattice-work, scroll, and shell ornamentation combined as shown.

The base A, which is supported on the legs A', has at each corner a lattice-work design a, surrounded by a plain ring a', and each foot has a lattice-work section a''. At the center of the panel is a lattice-work design a³, surrounded by broken scrolls a⁴, and below these scrolls are shell-like ornaments a⁵. Extending toward each end are scrolls a⁶ of the design illustrated, and on each end, extending down each leg, are scrolls in keeping with the main portion of the design.

The oven-door B has a shell-like scroll at each corner and a central ornamental panel inclosed by scrolls. Above the panel is a rosette and below the panel is a fan-like scroll.

The shell ornaments are connected by long scrolls, producing the design illustrated.

The fire-door D has a plain panel at the center and lattice ornaments at two corners diagonally opposite each other, and at one of the other corners is a shell-like ornamentation.

The ash-pit door E has a central rosette from which radiate a series of ribbed arms within a quadrant of a circle, and the upper surface of the door is ornamented in keeping with the rest of the door.

I claim—

1. The design for a cooking-stove as herein described and as shown in the accompanying drawing.
2. In the design for a cooking-stove, the base as herein described and as shown in the accompanying drawing.
3. In the design for a cooking-stove, the fire-door as herein described and as shown in the accompanying drawing.
4. In the design for a cooking-stove, the ash-pit door as herein described and as shown in the accompanying drawing.

In testimony whereof I have signed my name to this specification in the presence of two subscribing witnesses.

THOMAS I. RANKIN.
